UNITED STATES PATENT OFFICE.

ADELBERT S. JAQUITH, OF BOSTON, MASSACHUSETTS, ASSIGNOR TO GRANVILLE C. MITCHELL, OF MEDFIELD, MASSACHUSETTS.

SWIVEL CLENCHER-ARM.

1,155,818.

Specification of Letters Patent.

Patented Oct. 5, 1915.

Application filed June 30, 1914. Serial No. 848,498.

To all whom it may concern:

Be it known that I, ADELBERT S. JAQUITH, a citizen of the United States, residing at Boston, in the county of Suffolk and State 5 of Massachusetts, (whose post-office address is 42 Irwin street, Winthrop, Massachusetts,) have invented a new and useful Improvement in Swivel Clencher-Arms for Wire Stitching or Stapling Machines, of which 10 the following is a specification.

My invention relates generally to wire stitching or stapling machines, in which round or flat wire is fed into the machine and there formed into staples, which are instantaneously forced into the material of a barrel, 15 box, or container and clenched on the opposite side; and particularly to such machines driven by hand, foot or power, when adapted to and used for the purpose of fastening 20 together the component parts of square, rectangular, round or oval boxes, barrels and containers composed of paper, straw board, pulp board, binders' board and the like.

My objects in making said invention are: 25 first, to quickly and securely fasten together two or more pieces of the component parts of square, rectangular, round, or oval boxes, barrels or containers by means of wire staples; second, to provide a device so constructed as to be readily adjustable to the 30 different thicknesses, sizes and forms of boxes, barrels and containers usually composed of paper, straw board, pulp board, binders' board and the like; third, to provide a device that shall firmly clench the 35 wire staples as soon as they are driven through the box material; fourth, to perform its functions rapidly and with as great a degree of automatic action as possible.

I attain these important and valuable objects by means of the mechanism illustrated 40 in the accompanying drawings, in which—

Figure 1 is a perspective view of a wire stitching or stapling machine of the usual design and construction and having attached thereto my swivel clencher arm device; Fig. 45 2 is a front elevation of the same; Fig. 3 is a side elevation, the vertical column being broken to show a vertical section of the 50 right angle supporting arm for the swivel clencher arm; Fig. 4 is a cross section, on an enlarged scale, of the clencher arm, on the line x, x , Fig. 2; Fig. 5 is a side elevation of the parts shown in Fig. 4; Fig. 6 is a

plan view, on an enlarged scale, of my device, the column of the machine being shown in horizontal section; Fig. 7 is a front elevation, partly in vertical section, of the stitching head, the wire feeding and forming devices, with the operative parts in position for commencing the formation of the staple shown in vertical section; Fig. 8 is a vertical section of these operative parts at right angles to the section shown in Fig. 7; Fig. 9 is a vertical section similar to that shown in Fig. 8, but showing the parts in position for the second operation of staple forming; Fig. 10 is a vertical section of the same parts at right angles to the section shown in Fig. 9; Fig. 11 is a vertical section similar to that shown in Fig. 10, but showing the operative parts in position for the final operation of clenching the driven staple, and Fig. 12 is a vertical section of these parts at right angles to the section shown in Fig. 11.

Similar reference letters refer to similar parts throughout the several views.

The construction of my device and its application to a wire stitching or stapling machine is as follows:

Referring to Fig. 1, A, is the vertical supporting column of the machine, having a base a , resting upon the floor. Formed upon the top of this column A, is a horizontal head piece a' , in which is journaled a horizontal shaft having upon its rear end the driving pulley B, which is detachably attached to said shaft by means of a clutch operated by the foot lever b. Upon the front end of said shaft is fixed the cams operating the staple forming and driving mechanism and the staple wire feeding mechanism, commonly known as the stitcher head, and hereinafter more particularly referred to, and all of which is of the usual and well known construction and operation. Fixed to the vertical column A, is the bracket C, upon which is formed the vertical dovetail projection c, to which is fitted the right angle supporting arm D, the outer end of which is bored vertically to receive a similarly formed part e, upon the lower end of the clencher arm E. This arm is tapered from its base upward and rises at an inclination, its upper end being directly under the staple forming mechanism in the stitching head of the machine proper. This

- is its operative position. The clencher arm E, swivels or swings to the front and left whenever it is necessary to move its upper end from its operative position.
- 5 When in its operative position it is locked by the locking pin F, (Fig. 6,) which slides in its holder f, fixed to the top of the right angle arm D. The locking pin F, is fitted to enter the slot in the locking block d, fixed 70 to the flange at the base of the clencher arm E, as shown in Fig. 6. This locking pin is withdrawn from contact with the locking block d, by means of the foot lever G, acting through the rock shaft G', lever g, 75 connecting rod g', and the right angle lever g'', (Fig. 3,) and is forced into the locking block slot by means of the helical spring f''. The right angle arm D, clencher arm E, and its connections are vertically adjustable 80 by means of the screw d' and hand wheel d'', and clamped in any position desired by the clamping lever e', so that various thicknesses from 0 to $\frac{1}{2}$ inch can be stapled.
- 25 Referring to Fig. 6 it will be seen that the right angled arm D, is divided by a narrow vertical slot, thereby providing for a slight variation in the width of the vertical dovetail slot inclosing the dovetail e, 85 which is formed upon the bracket C, fixed to the vertical column A. Passing in a horizontal direction through the right angled arm D, is a clamping screw, upon the end of which is fixed the clamping lever e', 90 by which it may be tightened or loosened at will. These parts are constructed in the ordinary and well known manner usual in such cases.
- The foot lever G is adjustable upon the 95 rock shaft G', by means of its divided end and clamping screw z. When the locking pin F, is withdrawn from the locking slot in the locking block d, the clencher arm E, is swung to the front and around to the left 100 by means of the helical spring h, acting upon the connecting rod h', which is pivoted to the cap plate lever H, fixed to the lower end of the cylindrical part e, of the clencher arm E.
- 50 In the operation of driving and clenching the ordinary staple through flat work there are five distinct operations, namely: first, to feed in the wire; second, to cut off the piece of wire of the proper length to form 105 the staple; third, to form the staple with its ends projecting downward, ready for driving; fourth, driving the staple; and fifth, clenching the points of the staple tightly and firmly. In driving a staple through two pieces of material at right angles, as the corner of a box, an additional function is required, that of turning the ends inwardly, toward each other so as to 110 pass through the material at nearly a right angle on each side of a vertical center line

of the work, the material being at an angle of 45 degrees. The first four of the operations above recited are performed by the mechanism above the clencher arm, and the fifth, or final operation by the mechanism of the clencher arm itself. This mechanism is provided with guides and gages for supporting and retaining the material to be stapled in its proper position. These requirements are met by the clencher 75 arm E, its appendages and operative parts as follows:

Referring to Fig. 2, a vertical rod I, (shown in dotted lines,) is connected with the vertical cam rod of the stitching head K, in the usual manner. Its lower end is pivoted to the bell crank i, (shown in dotted lines,) whose upright portion is connected by the rod j, with the lever L, which is fixed to the rock shaft M, to which is 85 fixed the lever N, which in turn is connected with the bell crank O, by the swivel rod k. The bell crank O, is connected by the rod l, with the bell crank P. This is connected with the clencher Y, by the rod m. By this 90 mechanism the operative parts in the stitching head K, and those of the clencher arm E, work in unison in forming and driving and also in clenching the staple.

For the purpose of supporting the box, 95 barrel or container and its component parts to be stapled, the supporting guide loop R, is provided. This is detachably attached to the block r (Figs. 4 and 5,) by the thumb screw S. The block r, runs in a dovetail 100 slot formed in the upper surface of the clencher arm E, making it adjustable at any point along the length of said arm, and therefore providing a support for all sizes 105 of boxes, barrels, containers and covers within the range of the device, as shown in Fig. 1. Upon the block r, is also the gage n, having a projecting lip as shown, and secured by the thumb nut q, which serves to 110 gage all thicknesses and forms of boxes and covers, and particularly to support the rims of box covers.

The outer side of the inclined arm E, and the outer side of the inclined head T, constitute 115 respectively a box-body-supporting face, and a box-end supporting face, said faces being oppositely inclined relatively to the path in which the staples are driven, and meeting to form a right angled box-corner-supporting apex. The wire stitching head is organized and arranged to so drive each staple that one leg passes at one side of the apex through the body member, and the other leg at the opposite side of the apex 120 through the end member of a box y, supported by said faces. The oppositely inclined end faces on the reciprocating clencher are arranged to clench the two staple legs simultaneously against the inner 125 surfaces of the box body and box end. The 130

neck of the staple is bent by the driving mechanism across the box corner supported by the apex, said apex and corner forming an anvil across which the staple neck is bent. The upper side of the inclined arm E, and the apex formed by the junction of said arm and the head plate T, are curved as indicated by Figs. 8, 10 and 12, and by dotted lines in Fig. 1, the form of said upper side and apex being such that the assembled body and head of a substantially circular container are adapted to rotate on the arm and head plate, so that the continuous circular corner formed by the intersection of the container body and head is movable in an endless circular path in which the said apex is located. The staples are, therefore, driven in an endless circular series, as indicated in Fig. 1, without removing the work from the arm and each staple is spaced from the one previously driven, by imparting a sufficient partial rotation of the body and head of the container to cause the last staple to leave the apex and bring another portion of said corner onto the apex in position to receive the next staple.

The upper end of the clencher arm E, is formed at right angles to its upper side and to it is fixed the head plate T, which serves as a broader support for the work.

The operation of my device is as follows: The swivel clencher arm is placed at an angle of 45 degrees, so that when a barrel, ring, or cylindrical part of a round or oval box, barrel or container is placed upon it, and the top or bottom of said box, barrel or container is placed on the head plate of the clencher arm, the edges of both the barrel or ring, and of the top or bottom meet so that a 90 degree staple will securely fasten both together when properly driven. The object of placing the clencher arm at an angle of 45 degrees is to allow a symmetrical staple of 90 degrees to be properly driven into the box at the point where the edges meet, as already described.

Operation No. 1: The swivel clencher arm being in position to receive the barrel, ring, or cylindrical part of the box; the operator places the barrel, ring, or cylindrical part on the arm and in turn pushes the swivel clencher arm into its operating position where it is automatically locked. Then by placing the top or bottom, (as the case may be,) of the box, barrel or container on the head plate of the arm, so that the edge of the barrel, ring or cylindrical part, and the top or bottom of the box, barrel or container meet, the box is ready to receive the staple.

Operation No. 2: In stapling boxes, the operator places one hand on the barrel, ring or cylindrical part of the box as it rests on the swivel clencher arm, and the other hand on the top or bottom of the box, barrel or container as it rests on the head plate of the

swivel clencher arm, and in this manner turns the component parts of the box into position for receiving the successive staples.

Operation No. 3: When the box, barrel or container is completely stapled, the operator by pressing the foot lever unlocks the arm, which automatically swings toward the operator and stops in a position which allows the operator ample room between the swivel clencher arm and the stitcher head to remove the completed box. This operation is repeated, the foot lever G, depressed, the locking pin F, released, the helical spring h, acting through the plate lever H, swinging the clencher arm forward and to the left, when the completed box y, may be removed, another put in its place, the clencher arm swung back into its first or operative position, automatically locked, and the above described series of operations repeated.

Having thus described my invention and pointed out wherein it differs from previous devices and is therefore an improvement accomplishing a new and useful result, I claim:

1. In a wire stitching machine of the character described, the combination of a stitching head provided with a staple forming and driving mechanism of the usual construction to form and drive wire staples, an inclined clencher arm adapted to support the material to be stapled and arranged to swivel into and out of its operative position, a vertically adjustable support for said arm, a clencher sliding vertically in said arm, and means for operating said clencher in unison with the staple forming and driving mechanism in said stitching head.

2. In a wire stitching machine of the character described, a bracket fixed to the supporting column of said machine and having a vertical dovetail face formed thereon, a right-angled arm arranged to fit and slide vertically upon said bracket, a vertical screw to support and vertically adjust said right-angled supporting arm, an inclined supporting and clencher arm arranged to fit into and swivel upon said right-angled supporting arm, and means for locking said inclined clencher arm in its operative position.

3. In a wire stitching machine of the character described, an inclined clencher arm, a support adjustably fixed to said machine, the arm being swiveled upon said support, a sliding member arranged to lock said inclined clencher arm in its operative position, a spring arranged to operate said sliding member, means for releasing said sliding member by a foot lever, a horizontal sliding plunger pivoted to said inclined clencher arm, and a spring arranged to move said plunger and swing said clencher arm away from its operative position.

4. In a wire stitching machine of the character described, the combination of an inclined clencher arm, a head plate fixed at a right angle to said clencher arm, said 5 clencher arm and said head plate being adapted to support the component parts of a box, barrel or container to be operated upon, said clencher arm being arranged to swivel into and out of its operative position, 10 and means for driving wire staples and for clenching said staples when driven through said material, substantially in the manner described.

5. In a wire stitching machine, in combination, staple forming and driving mechanism located at an elevated point and including, first, means for feeding the staple wire, secondly, means for cutting off the wire in staple lengths, thirdly, means for 20 forming a staple with its ends projecting downward, and, fourthly, means for driving the staple downwardly, an inclined arm held under said mechanism against vertical movement during the operation of the machine, a head plate fixed at a right angle to said arm, the arm and head plate meeting to 25 form a curved corner supporting apex and being formed to support respectively a circular container body and a flat container head associated therewith and to permit the rotation of said container body and head on said arm and head plate while supported thereby, staple clenching mechanism car-

ried by said arm and including a vertically movable clencher acting in opposition to the 35 staple driving means above the arm, and means within the arm for vertically reciprocating said clencher, the continuous circular corner formed by the intersection of the container body and head being movable by 40 rotation in an endless path in which said corner supporting apex is located, so that the staples may be driven in an endless circular series without movement of the arm.

6. In a wire stitching or stapling machine 45 of the character described, and having an inclined and swiveling clencher arm supported upon an arm fixed to the vertical column of said machine or some fixed part thereof, the combination of a vertical rod attached to the 50 cam rod of said machine, a connecting rod passing through said supporting arm, a vertical rod provided with a swivel joint, a connecting rod within said inclined clencher arm, a clencher, a vertical rod in the head of 55 said clencher arm and pivoted to the clencher, and bell cranks connecting said series of rods and arranged to communicate motion from said cam rod to said clencher, substantially in the manner and for the purposes described.

ADELBERT S. JAQUITH.
